INTROVERSION SYRINGE

George N. Hein, San Carlos, Calif.; Howard T. Hein and George N. Hein, Jr., executors of said George N. Hein, deceased

Application February 17, 1945, Serial No. 578,398

8 Claims. (Cl. 128—215)

1

This invention relates to improvement in syringes and containers for use therewith, and more particularly relates to invagination, intussusception or introversion syringes and containers which for purposes of this application may be defined as a syringe of the type which includes a hollow container, having its wall material suitable for introversion inwardly upon itself longitudinally of the longitudinal axis of the container. Such containers may be made of any suitable pliable material, examples of which are hereinafter set forth.

Among the objects of the invention are to provide a syringe and a container for use therewith whereby the contents of the container may be ejected by extrusion responsive to introversion of the container upon itself. Another object is to provide a syringe and a container for use therewith wherein the discharge end of the container may automatically close upon release of pressure upon the opposite end of the syringe or upon removal of a perforating dispensing needle, if the latter is employed. A further object is to provide a container for use in dispensing extrudable fluids, semi-fluids, emulsions, pastes, and the like, and particularly for employment in syringes.

With the foregoing and other objects in view, the invention includes the devices and parts more particularly described in the following specifications and illustrated in the accompanying drawing, it being understood that changes may be made in form, dimension and minor details of construction without sacrificing any of the advantages of, nor departing from the spirit, of the invention as set forth in the claims appended hereto.

In the accompanying drawing which is illustrative of one form in which the invention may be embodied:

Fig. 1 is longitudinal section of syringe body and container, which illustrates in broken lines an operative position of parts.

Fig. 2 is a longitudinal view of the container body of Fig. 1, partly broken away and sectioned.

Fig. 3 is a fragmentary longitudinal section of a portion of syringe body similar to Fig. 1 and modified form of container.

Fig. 4 is a fragmentary view in section of a modified form of syringe body and container.

Fig. 5 is a longitudinal section view of a cannula and internally threaded holder, for use with structure of Fig. 4.

Fig. 6 is longitudinal section, partly in full line, of modified form of the invention.

2

Fig. 7 is a fragmentary longitudinal section view of a modification of the invention.

Fig. 8 is a longitudinal sectional view of a modified form of container.

- 5 In the drawing which is hereby referred to as a part of this specification, like reference characters indicate functionally corresponding parts in the several views insofar as practicable.
- In Fig. 1, a syringe body generally indicated 10 10 is provided with an elongated cylindrical barrel 11 circular in transverse section and open at its top or filling end 12 and having its opposite discharge end flanged inwardly at 13 providing an internal recess 14 and also providing a base for 15 an extended end nipple 15 which is externally threaded as at 16. The nipple 15 has an opening 17 therethrough communicating with the recess 14, the opening 17 being adapted for receiving therethrough an end portion of a cannula 18 20 which is held in mounted relation on the nipple 15 by a suitable threaded cannula holder or nut 19.

- The filling end 12 of the syringe body is closed by any suitable plug 20 which has an opening 21 25 centrally therethrough to receive and guide a piston 22 which is circular in transverse section. One end of the piston has a thumb pressure cap 23 and the opposite end, or plunger end is rounded as at 24. The piston 22 may have calibrations 25 which are desirable if the syringe barrel is of glass. Many modifications of specific syringe body structures may be employed according to the type of container to be employed therein, several modifications being illustrated in the 30 several views herein. However, it is preferable that the rounded plunger end 24 of the piston 22 be present regardless of the other details of syringe structure, and also that the outer diameter of the piston and the inner diameter of the confining wall of the barrel 11 shall be such that the space therebetween, and especially at the plunger end portion of the piston, shall be substantially twice the thickness of the wall of the introvertable container 26 which is received 35 therein, allowing, of course, for operational slideable clearances.

- A hollow container 26 is provided for mounting within the barrel 11 of the syringe. The container 26 may hold any material which may be 40 discharged by extrusion, whether liquid, emulsion, paste or the like. The container 26 is preferably elongated and also preferably circular centrally in lateral transverse section, and its length and diameter, respectively, are less than corresponding internal dimensions of the confining 45 55

wall of the syringe barrel, so that the container may be completely received within the barrel. It may be made of any suitable pliable material which may be introverted or invaginated upon itself, such as, for example, thin pliable foils of tin, lead, aluminum and the like metals, pliable sheet material of rubber, cellulose, plastics, impregnated cloth or paper and the like. The closed end of container 26 and also of the container in each modification hereinafter described, is integral with the side wall and is preferably formed with a concaved depression therein as at 27 so that the inward folding or introversion thereof is initially started prior to exertion of pressure thereon by the rounded end 24 of the piston. It is to be understood, however, that by providing the rounded end of the piston (see 24 and 24c of the drawing), a concavity will be made in the closed end of the container upon initial pressure of the piston thereon, even though the closed end of the container be pre-formed flat or even if it be pre-formed somewhat convexed. Upon pressure of the rounded end of the piston at this closed end wall of the container, the wall of the container collapses or folds inwardly upon itself and thereby extrudes the content of the container 26 from the discharge end 28. In Fig. 1, the container is illustrated in dotted lines in its full or uncollapsed position, and is shown in full line in its introverted or invaginated position. It is also to be understood that the container material is not specifically limited herein to a particular thickness, and the thickness thereof would depend on the characteristics of the material of which it is made, but the diameter of the piston should remain such that the wall of the piston is relatively spaced from the inner wall of the syringe barrel a distance which is substantially twice the thickness of the material of the container.

The container 26 also may have many modifications particularly at its discharged end. In the container of Figs. 1 and 2 the discharged end has a relatively short tubular extension 28 which is sealed and is adapted for seating in the recess 14 of the syringe barrel and is also adapted to have its sealed discharged end 28 punctured by the cannula 18. In the container of Fig. 2 the entire container body may be integral and of a pliable elastic material such as sheet rubber or partially elastic material, such as a gelatinous composition, or a flexible and pliable plastic material. When the container is of elastic or partially elastic material the opening or puncture therein made by the cannula 18 will automatically close upon removal of the cannula.

As shown in Fig. 3, the container body 26a may be also made of different material than the discharge end, such as metal foil for the walls of the container 26a and an elastic puncturable cap 28a for mounting on the discharge end. This type of container would be employable in the same type of syringe structure as is shown in Fig. 1, in which case recess 14 would obviously be made of sufficient diameter to receive the cap 28a.

In the modification illustrated in Fig. 4 the container 26b may be a pliable metal foil tube, and its inwardly flanged discharge end portion 29 thickened to provide a tube end closure and to provide an integrally mounted threaded nipple 30 which may be opened and closed by a removable threaded cap 31 which, when removed, permits the mounting of a cannula holder 19b and needle 18b of Fig. 5 directly on the nipple of the tube without necessity of puncture of the dis-

charged end of the container. In this construction of Fig. 4 the syringe barrel 11b has an opening 32 at the discharge end for receiving therethrough the nipple and cap of the tube container 26b. The advantage of the invention as exemplified by the structure of Fig. 4, is that it is particularly adapted for use with a type of collapsible tube container well known and in use on the present commercial market for tooth paste, shaving cream, ointment and the like, wherein the discharged end of the tube may be manually opened and closed. However the known tubes do not have a concaved end at the permanently closed end of the container, as described above and shown at 27 in the container of Fig. 2.

In the modification illustrated in Fig. 6 the discharge end of syringe barrel 11c has an internally threaded recess 33 for receiving therein the threaded nipple 34 of the cannula holder 19c. In the modification of Fig. 6 the discharge end of the barrel 11c has wall 35 at the base of recess 33 provided with an opening 36 therethrough, and the cannula holder 19c is provided with a recess 37, the open end of which registers with the circumference of the opening 36. The container 26c is a flexible elastic introvertible body such as rubber or gelatinous plastic, which has its discharge end elongated in the form of a resilient elastic tubular nipple 38 having a slotted puncture 39 at its discharged end. The opposite or closed end 40 of the container, in its normal filled position is preferably concaved similar to the container 26 in Figs. 1 and 2 but is provided with a filling opening and tubular neck 41 centrally of said end. The neck may be closed by a cork 42 which, if desired, may be provided with a circumferential groove 43 which the flexible body portion of the neck may engage for tightly closing the opening of the neck. Obviously, a thread or wire, not shown, may be employed in the groove to further bind the neck to the cork. In this modification a plunger member 22c of relatively larger diameter may be employed to provide space at its rounded end 24c for a recess 44 for receiving the neck 41 and the cork 42.

In the modification of Fig. 7 the syringe barrel 11d may be substantially similar to that shown in Fig. 4 and provided with an opening 32d at its discharge end, the hollow elongated resilient elastic discharge nipple 38d being received through the opening. The body of the container 36d is of flexible elastic material as in the container 26c of Fig. 6, and the discharge end of the nipple is similarly provided with a puncture or slit 39d. The piston 22d may also be similar to the piston 22 of Fig. 1.

The purpose of the puncture or slit 39 and 39d respectively in the nipples of Figs. 6 and 7 is to provide for opening the discharge end of the container solely responsive to the pressure of the piston on the opposite end of the container for extrusion of the contents thereof, and the automatic closing of the discharge end of the nipple due to its resilience upon release of that pressure of the piston. Since there will be a slight, though appreciable rebound or suction of the extruded material when the extruding pressure ceases, the material in the immediate region of the slit or perforation 39, 39d will be sucked slightly inwardly, thus permitting the slit or perforation to instantly close and sharply cut off any drip which might be anticipated.

In the modification of Fig. 8 there is disclosed a modified form of container body designated 26e which in this instance is particularly adapted to

facilitate filling. The container body may be made of any suitable introvertible material and is formed as a member separate from its closure member 45. The container body, when formed, has one end open whereby it may be readily filled, after which the closure member 45 is inserted in the open end. The closure member is of a readily perforable material such as rubber and has opposed recesses 46, 47, so that it may be punctured by a cannular needle when the container is placed in a syringe barrel and a cannula is attached to the discharge end of the syringe body. The closure member is provided with a collar flange 48 which may be raised while the end portion 49 of the open end of the container is flanged into the closure member, whereupon the collar flange 48 is pressed tightly upon the flange portion of the container end.

The characteristic of introversion of the container is generic to each of the containers illustrated and described in all forms of the invention, as well as the characteristic that the respective diameters of the interior of the syringe barrel and the exterior of the piston therein are relatively such that the piston wall is spaced from the inner barrel wall substantially twice the thickness of the material of the wall of the container, and it is highly preferable that the closed end of all the containers have an initial concavity.

It is to be understood that when the piston is being pressed upon the end of the container to introvert same the pressure upon the contents within the container is theoretically the same in all directions and at all points. Practically there may be some doubt as to whether the internal pressure is the same adjacent the discharge orifice as at the opposite end of the container when a semi-fluid emulsion or paste is being employed in the container. In practical operation, however, the internal pressure of the fluid in the container against the side walls of the container body is sufficient at all points to maintain the wall of the container in contact with the internal barrel wall of the syringe, so that the container wall is telescopically introverted upon itself as the piston is advanced. For support of the container wall when this pressure is exerted, the container should be of lesser length than the internal axial length of the barrel. And since the space between the piston and the cylinder barrel is substantially twice the thickness of the material of the container wall the introverted wall of the container is folded inwardly upon itself with the layers thereof in substantially superficial contact as shown in the drawing. Inasmuch as the piston, as it is advanced occupies the remainder of the lateral area transversely of the container, all of the contents of the container is completely and cleanly extruded. Such an arrangement of syringe barrel, piston and container, provides for inverting the container wall progressively within the body of the container parallel with the syringe axis, so that at all positions of introversion the introverted wall of the container closely parallelly overlies the externally surrounding container wall portion which is not introverted, and both of said container walls during introversion will be parallel with the barrel wall. This result is accomplished because the enclosing barrel of the syringe is cylindrical and the container therein is cylindrical, and upon pressure of the piston, spaced as aforesaid from the inner barrel wall, the container cannot expand outwardly. Therefore, considering the normal cylindrical container wall as its datum position,

the container wall is introverted through an arc of 180°, whereby, what may, for brevity be termed an acute angle of substantially zero degrees is formed where the two body layers of the container wall meet at the edge of the infold, since the outer container wall and the inner or introverted container wall are in overlying closely spaced parallelism, and preferably in slidably substantially superficial contact to completely exhaust the container. Such an introversion avoids a rebound of the infolded wall which would otherwise suck air into the opposite punctured discharge end of the container upon release of pressure of the piston. Introverting the wall of the container upon itself in this manner eliminates suck-back upon release of pressure of the piston, since the container walls will thus be relatively positioned beyond the angle of elastic rebound; and the double thickness of the container wall between the piston and barrel will serve as a packing gland to prevent the material in the container from by-passing the piston head and back between the introverted walls of the container. Such an introversion of a cylindrical container within a cylindrical barrel provides accuracy of extrusion from the container. For example, by depressing the piston a predetermined distance, a like volume of the contents of the container will be dispensed.

Having thus described the invention what is claimed as new and patentable is:

1. A syringe having a cylindrical barrel provided with a discharge end, a piston reciprocable in the barrel, in combination with a hollow container having a cylindrical body portion of less respective diameter and length than the corresponding internal dimensions of the syringe barrel, so as to be receivable completely within the confining wall of the barrel and having a discharge end positionable at the discharge end of the syringe barrel and having its opposite end closed, said container having a body side wall of flexible material introvertible upon itself responsive to pressure of the piston at the closed end thereof, the outer diameter of the piston and inner diameter of the barrel being relatively spaced substantially twice the thickness of the material comprising the side wall of the container, whereby at all positions of introversion of the container wall, the inner barrel wall, the outer container wall and the inner introverted container wall, will be maintained substantially parallel to the syringe axis and overlying relatively, and an angle of substantially zero degrees maintained between the overlying walls of the container at the connection thereof as the inner wall is progressively introvertedly telescoped by the piston into said parallel overlying relation with the outer container wall and inner wall of the barrel.
2. A syringe having a cylindrical barrel provided with a discharge end, a piston reciprocable in the barrel provided with a rounded plunger end, in combination with a hollow container having a cylindrical body portion of less respective diameter and length than the corresponding internal dimensions of the syringe barrel, so as to be receivable completely within the confining wall of the barrel and having a discharge end positionable at the discharge end of the syringe barrel and having its opposite end closed, said container having a body side wall of flexible material introvertible upon itself responsive to pressure of the piston at the closed end thereof, the outer diameter of the piston and inner diameter

7
of the barrel being relatively spaced substantially twice the thickness of the material comprising the side wall of the container, whereby at all positions of introversion of the container wall, the inner barrel wall, the outer container wall and the inner introverted container wall, will be maintained substantially parallel to the syringe axis and overlying relatively, and an angle of substantially zero degrees maintained between the overlying walls of the container at the connection thereof as the inner wall is progressively introvertedly telescoped by the piston into said parallel overlying relation with the outer container wall and inner wall of the barrel.

3. A syringe having a cylindrical barrel provided with a discharge end, a piston reciprocable in the barrel, in combination with a hollow container having a cylindrical body portion of less respective diameter and length than the corresponding internal dimensions of the syringe barrel, so as to be receivable completely within the confining wall of the barrel and having a discharge end positionable at the discharge end of the syringe barrel and having its opposite end closed and concave, said container having a body side wall of flexible material introvertible upon itself responsive to pressure of the piston at the closed end thereof, the outer diameter of the piston and inner diameter of the barrel being relatively spaced substantially twice the thickness of the material comprising the side wall of the container, whereby at all positions of introversion of the container wall, the inner barrel wall, the outer container wall and the inner introverted container wall, will be maintained substantially parallel to the syringe axis and overlying relatively, and an angle of substantially zero degrees maintained between the overlying walls of the container at the connection thereof as the inner wall is progressively introvertedly telescoped by the piston into said parallel overlying relation with the outer container wall and inner wall of the barrel.

4. A syringe having a cylindrical barrel provided with a discharge end, a piston reciprocable in the barrel provided with a rounded plunger end, in combination with a hollow container having a cylindrical body portion of less respective diameter and length than the corresponding internal dimensions of the syringe barrel, so as to be receivable completely within the confining wall of the barrel and having a discharge end positionable at the discharge end of the syringe barrel and having its opposite end closed and concave, said container having a body side wall of flexible material introvertible upon itself responsive to pressure of the piston at the closed end thereof, the outer diameter of the piston and inner diameter of the barrel being relatively spaced substantially twice the thickness of the material comprising the side wall of the container, whereby at all positions of introversion of the container wall, the inner barrel wall, the outer container wall and the inner introverted container wall, will be maintained substantially parallel to the syringe axis and overlying relatively, and an angle of substantially zero degrees maintained between the overlying walls of the container at the connection thereof as the inner wall is progressively introvertedly telescoped by the piston into said parallel overlying relation with the outer container wall and inner wall of the barrel.

5. A syringe having a cylindrical barrel with a discharge end, a piston reciprocable in the

barrel, provided with a rounded plunger end, in combination with a hollow container having a cylindrical body portion of less respective diameter and length than the corresponding internal dimensions of the syringe barrel, so as to be receivable completely within the confining wall of the barrel and having a discharge end positionable at the discharge end of the syringe barrel and having its opposite end closed, said container having a body side wall of flexible material introvertible upon itself responsive to pressure of the piston at the closed end thereof, the discharge end of the container having an elongated hollow nipple puncturable at the tip thereof, the outer diameter of the piston and the inner diameter of the barrel being relatively spaced substantially twice the thickness of the material comprising the side wall of the container, whereby at all positions of introversion of the container wall, the inner barrel wall, the outer container wall and the inner introverted container wall, will be maintained substantially parallel to the syringe axis and overlying relatively, and an angle of substantially zero degrees maintained between the overlying walls of the container at the connection thereof as the inner wall is progressively introvertedly telescoped by the piston into said parallel overlying relation with the outer container wall and inner wall of the barrel.

6. A syringe having a cylindrical barrel with a discharge end, a piston reciprocable in the barrel provided with a rounded plunger end, in combination with a hollow container having a cylindrical body portion of less respective diameter and length than the corresponding internal dimensions of the syringe barrel, so as to be receivable completely within the confining wall of the barrel and having a discharge end positionable at the discharge end of the syringe barrel and having its opposite end closed and concave, said container having a body side wall of flexible material introvertible upon itself responsive to pressure of the piston at the closed end thereof, the discharge end of the container having an elongated hollow nipple puncturable at the discharge tip thereof, the outer diameter of the piston and inner diameter of the barrel being relatively spaced substantially twice the thickness of the material comprising the side wall of the container, whereby at all positions of introversion of the container wall, the inner barrel wall, the outer container wall and the inner introverted container wall, will be maintained substantially parallel to the syringe axis and overlying relatively, and an angle of substantially zero degrees maintained between the overlying walls of the container at the connection thereof as the inner wall is progressively introvertedly telescoped by the piston into said parallel overlying relation with the outer container wall and inner wall of the barrel.

7. A syringe of the character described comprising the combination of a cylindrical syringe barrel provided with a discharge end, a piston reciprocable in the barrel provided with a rounded plunger end having a central recess, a hollow container having a cylindrical body portion of less respective diameter and length than the corresponding internal dimensions of the syringe barrel, so as to be receivable completely within the confining wall of the barrel and having a discharge end positionable at the discharge end of the syringe barrel and having its opposite end provided with a closable filling neck adapted for

reception in the piston recess, said closed end being concave circumferentially of said neck, said container having a body side wall of flexible material introvertible upon itself responsive to pressure of the piston at the closed end thereof, the outer diameter of the piston and inner diameter of the barrel being relatively spaced substantially twice the thickness of the material comprising the side wall of the container.

8. A container device for syringes comprising a cylindrical hollow elongated shell body for positioning in a syringe barrel, said container having a discharge end positionable at the discharge end of the syringe barrel, and having its opposite end provided with an extended closable filling neck of lesser diameter than the shell body, said container having a body side wall of flexible mate-

rial introvertible upon itself, the discharge end of the container having a closure.
